[57] **CLAIM**

The ornamental design for a combined magnetic heater and massager, substantially as shown and described.

DESCRIPTION

FIG. 1 is a side perspective view of a combined magnetic heater and massager showing my new design, the side opposite being substantially a mirror image; FIG. 2 is a side elevational view of a combined magnetic heater and massager;

FIG. 3 is a plan view of a combined magnetic heater and massager;

FIG. 4 is a cross-sectional view of a combined magnetic heater and massager taken along line I—I of FIG. 3; and FIG. 5 is a side view of the combined magnetic heater and massager of this invention, wherein the elements thereof have been pivoted to an alternate position; and FIG. 6 is a plan view thereof, wherein a human figure is shown in broken lines for illustrative purposes only.

FIG.1

FIG.2
